(57) **CLAIM**

The ornamental design for an electronic device with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with animated graphical user interface showing a first image of the claimed design;

FIG. 2 is a second image thereof;

FIG. 3 is a third image thereof;

FIG. 4 is a fourth image thereof;

FIG. 5 is a front view of another embodiment of an electronic device with animated graphical user interface showing a first image of the claimed design;

FIG. 6 is a second image thereof;

FIG. 7 is a third image thereof;

FIG. 8 is a fourth image thereof; and,

FIG. 9 is a front view of an electronic device, the first image of the animated graphical user interface of FIG. 1 applied thereto. The animated graphical user interface designs of FIGS. 2-8 may be similarly applied thereto.

The broken line circle in all figures shows an electronic device and forms no part of the claimed design. The outer broken line in FIG. 9 shows an alternate electronic device and forms no part of the claimed design.

The appearance of the animated image sequentially transitions between the images shown in FIGS. 1-4 and FIGS. 5-8, respectively. The process or period in which one image transitions to another forms no part of the claimed design.

1 Claim, 3 Drawing Sheets
